Maximilien
ATTORNEY

UNITED STATES PATENT OFFICE.

GOREGE GODULA, OF WYOMING, PENNSYLVANIA.

RAIL JOINT.

Application filed April 24, 1923. Serial No. 634,213.

To all whom it may concern:

Be it known that I, GOREGE GODULA, a citizen of Poland, residing at Wyoming, in the county of Luzerne and State of Pennsylvania, have invented certain new and useful Improvements in Rail Joints, of which the following is a specification.

This invention relates to railroad rail joints and fastenings and has as its main object to provide an exceptionally strong and rigid joint structure which can be applied to the abutting ends of the rails without change or fitting the same in any manner.

Another purpose is to produce rail joint devices which require no bolts to hold them in fixed relation to the rails avoiding drilling, punching or otherwise weakening the rails as well as the expense incurred.

A further object is to provide fasteners that dispense with fish plates and other like extra parts.

These objects and others, such as simplicity, economy and neatness of appearance are attained by the novel construction, combination and arrangement of parts hereafter described and shown in the accompanying drawing forming part hereof and in which:—

Figure 1 is a side elevational view of a pair of rails illustrating the application of the joint connection.

Figure 2 is a transverse sectional view taken thru the structure.

Figure 3 is a bottom plan view of the same.

In the drawing the numeral 5 designates a tie or sleeper and 6 the spikes used to secure the rails thereto.

These rails, which are of the usual type, are composed of a head 7, stem 8 and flanged base 9, and in the application of the present invention are merely cut across, no drilling, punching or other form of mutilating being required.

The invention resides in a pair of opposed chair elements 10 and 11 shaped to engage under the head of the rail and over its flanged base, presenting as nearly as possible a uniform thickness of wall from near the head to the outstanding edge of the flanges.

Integral with the chairs are inreaching elements 12 and 13 having semi-dove-tailed extensions 14 and 15 disposed below the

stem of the rail, as best seen in Figure 2, 55 said extensions being coincident in length with the full width of the chair and parallel with its edges.

A plurality of recesses 16 and 17 are formed in the chair edges to receive the heads of the spike 6, and in the lower surface of the elements 12 and 13 are angular longitudinal slots 18 and 19.

A bolster plate 20 is interposed between the ties 5 and chair bases, said plate having 60 inturned end edges raised to receive the corresponding edges of the chairs and are recessed as at 21 and 22 to permit passage of the spikes.

On the upper surface of the bolster are 70 raised angular ribs 23 and 24 extending transversely of the plate and suited to be received within the slots 18 and 19, thus positively locking the chairs against separation.

Due to the interengaging features of the chairs, the clamping effect obtained by the ends of the bolster plate and the interlocking ribs, it will be seen that an unusually strong, compact and secure fastening of 80 great simplicity has been disclosed in the preferred form of its embodiment, but it is understood that minor changes within the scope of the appended claims may be made.

Having thus described my invention, what 85 I claim as new and desire to secure by Letters Patent, is:—

1. A rail joint fastener comprising a pair of chair members disposed on opposite sides of abutting rails; said members completely 90 surrounding the bases of the rails at the point of application, interengaging elements formed cooperatively with the adjacent edges of said chair members and disposed in the plane of the rail webs, a bolster plate on 95 which said chair members rest, means at the ends of said plate for confining said chair members, and ribs on said bolster plate engaged in corresponding slots in the bases of said chair members.

2. A rail joint fastener comprising in combination with a pair of unmutilated abutting rails, a chair member on each side of the rails, said chairs being of substantially uniform thickness throughout, fitting the rails below their heads and enveloping their bases, interengaging elements formed with said chair members below the

stem of the rails, a bolster plate disposed below said chair members, said plate having raised inreaching angular edges adapted to engage the outer edges of said chair members, said chair members and bolster plate being correspondingly notched to receive fastenings, and raised angular ribs in the upper surface of said plate engaged in slots

correspondingly formed in the bases of said chair members. 10

In witness whereof I have affixed my signature.

GOREGE GODULA.

Witness:

W. R. GILLESPIE.
